UNITED STATES PATENT OFFICE.

THOMAS B. FIELD, OF NANTUCKET, MASSACHUSETTS.

IMPROVEMENT IN WIND-WHEELS.

Specification forming part of Letters Patent No. 43,675, dated August 2, 1864.

To all whom it may concern:

Be it known that I, THOMAS B. FIELD, of Nantucket, in the county of Nantucket and State of Massachusetts, have invented a new and Improved Horizontal Wind-Wheel; and I do hereby declare that the following is a full, clear, and exact description thereof, which will enable those skilled in the art to make and use the same, reference being had to the accompanying drawings, forming a part of this specification, in which—

Figure 1 is a plan or top view of my invention; Fig. 2, a vertical central section of the same; Fig. 3, a horizontal section of the same, taken in the line $x x$; Fig. 2.

Similar letters of reference indicate corresponding parts.

This invention relates to a new and improved horizontal wind-wheel of that class in which the wings or sails are turned automatically from an upright to a horizontal position, and vice versa, as the wheel is rotated in a horizontal plane under the action of the wind.

The object of the invention is to obtain a wind-wheel of the class specified which will operate with certainty and precision, and will be capable of turning in either direction—that is to say, either to the right or left, as may be desired.

A represents a framing, in which an upright shaft, B, is placed vertically and allowed to rotate freely. This shaft B has a horizontal rim, C, secured to it by radial arms a, forming what may be termed a "wheel," the rim C being of angle form in its transverse section, as shown clearly in Fig. 2.

D represents four horizontal shafts, the journals b at the inner ends of which are fitted in the shaft B, the journals c, which are a trifle beyond the centers of the shafts, having their bearings d on the rim C, and the portions of said shafts which extend beyond the rim C have each four rows of teeth, e, on them, arranged in spiral rows of three teeth each. The shafts D are allowed to turn freely in their bearings, and on each shaft, just inside of the rim C, there is placed a band, E, provided with four pins, f, at equal distances apart. These bands E are adjustable circumferentially to a certain degree on the shafts D, and they are secured on said shafts by set-screws g, passing through slots h in the bands, the slots h being of such a length as to admit

of a proper degree of adjustment of the bands, which is about the one-eighth of a revolution on the shafts. The pins f of the bands E, in connection with catches hereinafter described, are for the purpose of holding the shafts D and the wings or sails F, which are attached to them, in proper position during the intervals between their adjustment. The catches G are composed of two elastic plates, $a^x a^x$, notched at their outer ends to receive the pins f, said plates being secured at their inner ends to slides H, the outer parts of which pass through the rim C, the inner parts being fitted in the shaft B, each slide having a spring, b ^{x} , upon it, which springs have a tendency to keep the notched ends of the catches G over the pins f. (See Fig. 2.) By this arrangement it will be seen that in order to allow the shafts D to turn, the slides H must be pressed back in order to disengage the pins f from the catches G, and these pins, on account of the elasticity of the plates $a^x a^x$, are enabled to engage themselves with the catches, so as to hold the shafts.

I is a bar or plate which is fitted on the upper end, g, of the framing A, which is of annular form, and is clamped thereto by plates J, which are screwed to the under side of the bar I, and bear against the under side of the top of the framing, as shown in Fig. 2. On the bar I, near each end, is fitted a sliding plate, K. These plates work between guides h h on the bar I, and they are moved or adjusted in a direction longitudinally with the bar I by means of levers L. (Shown in Fig. 2.) These levers are retained in proper position at desired points in their movement by means of pins passing through them and through perforations in pendent segment-bars M, attached to the plate I. Each plate K is provided with three projections, i, on its upper surface, which, when the plates K are adjusted in a certain position, are in line with the teeth e of the shafts D, so that said teeth will come in contact with the projections i as they pass over the plates K. The plates K are also provided each with two projections, j j, at their inner sides, which are allowed to spring outward or yield in the direction in which the slides H move with the wheel, but are rigid in the opposite direction. (See Fig. 3.) These projections are beveled at their outer edges, and they serve to press inward the slides H

and release the pins *f* of the bands *E*, so that the shafts *D* may turn when the teeth *e* come in contact with the projections *i* on the plates *K*, the shafts turning just one quarter of a revolution each time they pass over the plates *K*. The wings or sails may be constructed in any proper manner and attached longitudinally and centrally to shafts *O*, which are secured in the ends of the shafts *D*. The turning of the shafts *D* by means of the teeth *e* and projections *i*, as described, causes the wings or sails to turn from a horizontal to a vertical position, and vice versa, the wing or sail on one shaft *D* being in a vertical position when the wing or sail on the opposite shaft is in a horizontal position; hence it will be seen that the wings or sails at one side of the wind-wheel are in a vertical position for the wind to act against and rotate the wheel, the wings or sails being turned down to a horizontal position as their shafts *D* pass over the plate *K* at the center of the rear or leeward side of the wheel, and being retained in such position until they arrive at the center of the front or windward side of the wheel, at which point the shafts *D* pass over the other plate *K* and the wings or sails are turned upward to a vertical position for the wind to act against.

The wind-wheel may be rendered inoperative at any time by adjusting the plates *E* so that their projections *i* will be out of line with the teeth *e*.

The wheel may be made to rotate either to the right or left, as desired, by adjusting the bands *E* on the shafts *D*, so as to regulate the position of the pins *f* relatively with the teeth *e* and cause the wings or sails to assume a vertical position at the side of the wheel where it is designed that the wind shall act.

I claim as new and desire to secure by Letters Patent—

1. The turning of the wings or sails from a vertical to a horizontal position, and vice versa, by means of the teeth *e* on the shafts *D* and the projections *i* on the adjustable or sliding plates *K*, or the equivalents of said teeth and projections, when used with the plates *K*, to operate substantially as and for the purpose set forth.

2. The bands *E*, provided with teeth *f*, in connection with the catches *G*, attached to the slides *H* for the purpose of retaining or holding the wings or sails during the intervals between their adjustment, substantially as described.

3. The projections *j* at the inner sides of the plates *K*, in combination with the slides *H*, to which the catches *G* are attached, all arranged, substantially as shown, for releasing the shafts *D* and admitting of the turning of the wings or sails, as set forth.

THOMAS B. FIELD.
